UNITED STATES PATENT OFFICE.

FREDERICK H. GIBBS, OF NEW YORK, N. Y., ASSIGNOR TO AMERICAN CAR AND FOUNDRY COMPANY, OF ST. LOUIS, MISSOURI, A CORPORATION OF NEW JERSEY.

UNDERFRAME.

1,140,672.

Specification of Letters Patent.

Patented May 25, 1915.

Application filed November 8, 1912. Serial No. 730,225.

To all whom it may concern:

Be it known that I, FREDERICK H. GIBBS, residing at New York city, New York, and being a citizen of the United States, have 5 invented certain new and useful Improvements in Underframes, of which the following is a full, clear, and exact description, such as will enable others skilled in the art to which it appertains to make and to use the 10 same, reference being had to the accompanying drawings, which illustrate the preferred form of the invention, though it is to be understood that the invention is not limited to the exact details of construction shown 15 and described, as it is obvious that various modifications thereof will occur to persons skilled in the art.

This invention relates to underframe construction for railroad cars and particularly 20 to that class of construction wherein rolled or pressed commercial sections are used in the formation thereof and comprehends in its adaptation means whereby the end and side sills and the center sill construction are 25 effectively fixed together independent of the bolsters and whereby the bolsters are reinforced from the center sill construction and from the end and side sills intermediate the span of the bolster and also whereby the 30 juncture of the end and side sills are reinforced from the center sill construction through the bolsters and supplementally reinforced from the said bolsters and the bolster forms a strut in the truss thus 35 formed.

This invention also comprehends in its adaptation means whereby the crushing strains caused by the impact of buffing to the end underframe members shall be directly transmitted therefrom to the center 40 sill construction through a center casting of particular construction which acts also as a bolster filler and reinforcement.

This invention also comprehends in its 45 adaptation reinforcing and bracing of the bolster webs in a plurality of planes vertical relatively to the longitudinal axis of the bolster and it also comprehends a novel construction for supporting the push pole 50 pockets.

Drawings.—Figure 1 represents a plan view of a part of the underframe illustrat-

ing one of the embodiments of this invention. Fig. 2 is a front view of the bolster illustrating the relationship of the parts and 55 taken on the line 2—2 of Fig. 1. Fig. 3 is a detail of the side bearing. Fig. 4 is a detail of interior bolster reinforcement and interior side bearing brace. Fig. 5 is a side elevation of the center casting taken on the line 60 5—5 of Fig. 1. Fig. 6 is a view of the interior of the corner of the underframe, showing 65 the details of the juncture of the side and end sills and the rear of the push pole pocket support on the line 6—6 of Fig. 1, looking in the direction of the arrow. Fig. 7 is a fragmental corner section, showing 70 the push pole pocket in position. Fig. 8 is a plan of a modification of this invention, wherein the bolster webs are arranged back 75 to back or a single I-beam bolster is employed, and, Fig. 9 is a front view of the bolster of this latter construction, showing the relationship of the parts as therein adapted and is taken on the line 9—9 of Fig. 8.

In the present adaptation of the invention, an I-beam form of center sill has been used as it is one of the objects of this present invention to practically eliminate the smashing force of an end impact, which has heretofore ruptured the connections of draft sills used with the single sill construction common in the art.

The ordinary Z-bar form of side sill and 85 the usual form of end sill are employed in this construction and the common form of channel shaped cross bearers or needle bars piercing the web of the center sill are also utilized. As these elements are common in 90 a great many constructions of this nature they will not be claimed herein, except as may be advisable in combination to form an operative underframe.

Referring particularly to the drawings, 95 the center sill 1 is of ordinary I-beam form reduced in depth at the ends where it approaches the bolsters so that the bottom flange may be inclined upward toward the upper flange for the purpose of forming a 100 truss shaped center sill.

The draft sills 2 are of the usual channel shape having their flanges turned outwardly and are secured to the end sills 3, which are

of the usual construction, by means of a connection plate 6.

The bolsters employed in this construction are preferably of the bath-tub type or of the 5 type wherein spaced webs are used and wherein the webs are provided with an out-turned flange 8, to which is secured a bolster cover plate 9. These bolsters are provided with the side bearing 10 and are also 10 provided with interior web spacing and side body reinforcing elements 11. The ends of the bolsters are provided with castings 12 which are adapted to fit closely within the 15 walls of the bolster and be secured thereto and are provided with a bracket portion adapted to fit and carry the Z-bar side sills.

The center casting 14 employed in this construction comprises a casting provided with webs 15 extending practically at 120° 20 to each other from the king pin socket as a center, and is also provided with flanges 16, two of which are adapted to abut against the inside of the bolster web immediately behind its juncture with the draft sills 2, 25 and one of which is adapted to abut against the web of the bolster substantially in line with the web of the center sill 1. These flanges are adapted to lie in two parallel planes conforming to the inner surface of 30 the bolster webs and afford riveting area for the center and draft sills. It will be seen from the construction of the draft sills and center sill construction that any crushing impact transmitted through the draft sills 35 will be immediately concentrated through the flanges 16 to the webs 15 of the center casting 14 to the webs 1 of the center sill construction and that the webs of the bolster would tend in a measure to assist in resisting 40 this crushing impact. The interior bolster reinforcement and side body brace 11 are arranged at an angle as will be more fully explained hereafter.

The diagonal brace 5, which in usual 45 constructions extended from the juncture of the end and side sills to the juncture of the draft sills and the bolsters, in this invention has been formed continuous from the juncture of the end and side sills through 50 the bolster to a point in proximity to the first cross bearer and the webs of the bolster have been provided with a perforation or pocket through which this diagonal brace extends and the interior bolster reinforcement and side body brace 11 has been arranged at an angle corresponding to the 55 angle of this diagonal brace. The diagonal brace is shown of channel section, (though any suitable section may be substituted) and 60 it is adapted to abut or rest upon the interior bolster reinforcement and side body brace 11 and the perforation in the webs of the bolsters on either side have been reinforced by angle irons 17 so arranged that

they shall fill the space between the flange 65 of the channel diagonal member 5 and be secured to the webs of the bolsters and close up the bolster web perforation or pockets. The diagonal brace 5 forms a diagonal chord and tension element in a truss composed of the end sill 3, draft sill 2, center sill 1 and the bolster 8, which is intersected by and fixed to the diagonal chord 5 at a point intermediate its span, and said bolster forms a strut for the truss thus formed. 70 The diagonal brace 5 also forms a diagonal chord and a compression member in a truss composed of the side sill 4, first cross-bearer 20, center sill 1, draft sills 2 and the bolster 8, the said bolster being intersected by and 75 fixed to said diagonal chord at a point intermediate its span and forming a strut for the truss thus formed. It will, therefore, be perceived that the entire end underframe construction as far as the first cross-bearer 80 comprises complementary trusses adapted to absorb and distribute end or side stresses transmitted to the underframe into the center sill construction, or, in other words, to utilize the leverage exerted by the said diagonal chord to maintain the conformation, 85 relationship and alinement of the underframe relative to the rest of the underframe. This is perhaps best illustrated by applying 90 a force inwardly at the corner of the underframe. The action of this force would immediately be transmitted to the diagonal chord 5 or lever, as it may now be termed, and could only travel to the point of junction of this chord with the bolster or to 95 the fulcrum of the said chord, and the power end of the chord or lever 5, which has been described herein, is secured to the center sill in rear of the bolster, which would tend, and, in fact, would force the 100 corner of the underframe outward or to normal position. The same operation would result were the force applied at the end sill or at the side sill or at the first cross-bearer, 105 in fact, at any point along the side sills. It will, therefore, be seen that the diagonal brace or lever 5 forms either a tension or compression element against stresses to the 110 underframe and that the leverage exerted by the said brace or lever forces the parts to normal position irrespective of the point of application of force or shock. In fact, this brace or lever renders it possible in the 115 construction disclosed in this invention to omit the side sills 4 in case the underframe 120 be used as a tank underframe, and the foundation afforded by this construction would provide the necessary end platform or support for the head blocks, usual in such construction.

It will be seen that the webs at the end of the diagonal channels 5 where the same join the end and side sill construction have been

turned backward so as to form a reinforcement 18 for the end sills and for the side sills and that this reinforcement, as particularly shown in Fig. 6 extends far enough 5 along the end sills to permit the insertion of a rivet hole to support one of the rivets of the push pole pocket.

As a further reinforcement at the point of juncture of the end and side sills, a plate 10 19 is riveted to the end and side sills to insure additional rigidity. The cross bearers 20 as has been before said extend through the center sills and are provided with brackets 21 at the extremities thereof for the purpose 15 of rigidly securing the Z-shaped side sills thereto. Angle pieces 22 have been provided for the purpose of riveting the cross bearers to the center sill on the flanged side thereof and angle pieces 23 for the purpose 20 of riveting the said cross bearers to the center sill web on the web side thereof. It will be seen from an inspection of the construction that any impact to the end sills will be transmitted to the draft sills 2 and to the 25 diagonal braces 5, but as the diagonal braces 5 are rigidly secured by means of angle irons 17 to the webs of the bolster, a part of said strain will be carried or absorbed in the said bolster and a part of it transmitted 30 through the said bolster, through the extension of the diagonal braces 5 to the center sill construction, and the direct impact to the buffer plates or striking castings 24 and to the draft sills 2 will be transmitted 35 through the center casting 14 to the web of the center sill construction so that all strains from impact will be absorbed practically by the bolster and center sill construction.

One of the advantages of this construction lies in the fact that the usual bath-tub bolster which is probably the most feasible of manufacture has been reinforced at the point where it has heretofore been defective; in other words, between the king pin and the 45 side sills and has been reinforced in such manner that it is capable of resisting as much if not greater strains than bolsters of other constructions and furthermore it has been reinforced in such manner at the center 50 so that it is impossible for any crushing impact, transmitted through the draft sills to the center sills, to effect it in any way whatever.

The cover plate 9 of the bolster construction not only adds rigidity to the said construction, but also provides a riveting area and securing means for the diagonal braces extending through the bolster webs from the juncture of the end and side sills to the 55 center sills.

In the modification shown in Figs. 8 and 9, bolster diaphragms 25 form somewhat deeper at the center than at the sides and placed back to back have been employed,

and upper cover plates 26 and lower cover plates 27 have been used to provide suitable attaching means for a side bearing 10 and for properly bracing the upper and lower flanges of said bolster diaphragms. The draft sill construction in this modification 65 70 extends to webs of the bolster diaphragms. The bolster webs 25 are provided with a king pin socket to which is attached a bracket 28 which is secured to the web of the center sill. The diagonal braces 5 are 75 of the same form and construction as in the preferred form of the invention and are secured to the web of the bolster by means of angle irons 17 as indicated in Fig. 5, 80 which angle irons serve not only to secure the diagonal braces at the web of the bolster diaphragms, but also serve as a reinforcement to the perforation in said diaphragms. The cross bearers and details of construction 85 in this modification are identical with the construction of Fig. 1 and need not therefore be described.

Another advantage of this invention is that the diagonal braces receive their support from the center sill construction and 90 do not necessarily depend upon the bolsters or draft sills for their resisting power except supplementally wherein the bolster acts as a form of strut in a truss formed by the side and end sills. 95

Another advantage attached to this invention is that when a push pole is used in the push pole pocket, the angle of the push rod in almost every instance will coincide with the direction of the angle braces 5 so 100 that the construction would receive no side strain from such uses.

What I claim is:—

1. An underframe construction comprising draft sills, a single center sill and a 105 through bolster, and a center casting spacing and supporting the bolster webs and adapted to converge the crushing stresses transmitted to the draft sills into the center sills.

2. In an underframe, a bolster provided 110 with pockets, a single center sill comprising a vertical web and a plurality of diagonal braces resting in said pockets and being connected together through said web.

3. In an underframe, a bolster provided 115 with pockets, end sills, a plurality of diagonal braces connected together at their inner ends and extending outwardly through said bolster and being connected with said end sills at their outer ends. 120

4. In an underframe, a single center sill, spaced draft sills, end sills, pocketed bolsters and diagonal braces connected to said single center sill and extending through the pockets of said bolsters to connect with said end sills. 125

5. In a car underframe, Z-shaped side sills, a single center sill, a pocketed bolster and diagonal braces connected directly together.

- through said center sill extending through the bolster pockets and terminating below one of the flanges of each of said side sills.
6. In a car underframe, Z-shaped side sills, a single center sill, a pocketed bolster and diagonal braces connected directly together through said center sill extending through the bolster pockets and connected to the webs of said side sills.
- 10 7. In an underframe, a single rolled center sill having vertical web, a bolster, spaced draft sills, an end sill, flanged side sills connected with said end sill, and diagonal braces connected together through the web 15 of said center sill extending thence through said bolster and to near the juncture of said side and end sills.
8. In an underframe comprising a single plate-girder center sill between bolsters, a 20 bolster, an end sill, spaced draft sills, and diagonal braces extending from near said end sills through said bolster and being connected together by means connecting said braces to the plate of said center sill.
- 25 9. In an underframe comprising a single plate-girder center sill between bolsters, bolsters, end sills, spaced draft sills extending between said end sills and bolsters at each end, and braces adapted to aid in supporting said end sills, said braces extending from said end sills through said bolsters and being connected together through said plate-girder sill intermediate said bolsters.
- 10 30 10. In a single center sill construction, means for supporting the outer ends of spaced draft sills comprising an end sill and diagonal braces fulcrumed at a bolster and extending from said end sill to and being connected together through said single center sill.
11. In a car underframe, a bolster, an end sill, and diagonal braces for said end sill fulcrumed at said bolster with the major portion of their length extending inwardly of said bolster and being rigidly supported at their inner ends.
12. In a car underframe, a flanged center sill having a vertical web, Z-shaped side sills, a bolster connecting said sills, and 45 diagonal braces fulcrumed at said bolster and being connected together at one end and being connected to the webs of said side sills beyond said bolster.
13. In a car underframe, a single plate-girder center sill, spaced draft sills, a filler casting connecting the draft and center sills, a bolster provided with pockets, and diagonal braces resting in said pockets and being connected directly to said plate-girder 60 sill and adapted to aid in supporting the outer end of said underframe.
14. In a car construction, bolsters, and an end sill support comprising levers connected with said end sill at their outer ends and be- ing connected directly together at their inner ends intermediate said bolsters.
15. In a car underframe, bolsters, a single center sill terminating at said bolsters, channel-shaped draft sills extending outwardly from said bolsters, end sills extending across said draft sills intermediate their ends, and diagonal braces connecting said ends sills with said center sill between said bolsters.
16. In a car underframe, bolsters, a single center sill terminating at said bolsters, channel-shaped draft sills extending outwardly from said bolsters, end sills extending across said draft sills intermediate their ends, and connected diagonal braces fulcrumed at said bolsters and being connected directly to the 75 single center sill intermediate said bolsters.
17. In a car underframe, bolsters, a single rolled center sill, end sills, spaced draft sills formed of rolled flanged sections longer than the distance between said bolsters and 80 said end sills, bolster cover plates connecting said center sill and said draft sills, and diagonal braces connecting the end sill and single center sill.
18. In a car underframe, bolsters, end sills 85 and intermediate means connecting said bolsters, in combination with bolster reinforcing means penetrating said bolsters and extending diagonally from near the outer ends of said end sills to said intermediate connecting means.
19. In a car underframe, bolsters, end sills, a single center sill connecting said bolsters, in combination with bolster reinforcing means penetrating the bolsters and being 90 connected with said end sills near their outer ends and with the center sill intermediate the bolsters.
20. In a car underframe, bolsters, a center sill, end sills and diagonal braces connected through the center sill and with the end sill and combined with the elements of 95 said bolsters in such manner as to form stiffening members for the bolsters vertically thereof.
21. In a car underframe, bolsters provided with side bearings, a single center sill connecting said bolsters, end sills, and diagonal braces connected with said center sill at one 100 end, penetrating said bolsters in alinement with said side bearings, and connected with said end sills at their opposite ends.
22. In a car underframe, bolsters, end sills, spaced draft sills terminating at said 105 bolsters, and means for supporting the outer ends of said draft sills comprising a center sill and diagonal braces connected through said center sill intermediate the bolsters, passing thence through the bolsters and connected with the outer ends of the end sills, 115 the end sills being connected with the draft sills.
23. In an underframe, bolsters, a single

center sill spanning the space between said bolsters, spaced draft sills, end sills connecting the outer end portions of said draft sills, and diagonal braces connected with said center sill, passing thence through the bolster and being connected with said end sills near their outer ends.

In witness whereof I have hereunto set my hand in the presence of two witnesses.

FREDERICK H. GIBBS.
